RECTIFIER

Application filed July 20, 1927. Serial No. 207,073.

This invention relates to an electron discharge device and more particularly to a glow discharge device employing a rarefied gaseous atmosphere.

5 The invention is especially concerned with the production of a gaseous conduction rectifier of alternating current, employing a monatomic gas filling, such as helium, argon or neon or a mixture of such gases, and depending at least in part, upon the point to plate discharge principle for rectification.

Hitherto, considerable difficulty has been experienced in producing alternating current rectifiers of this type capable of operation at 15 relatively high potentials, which depend on gas ionization for conduction of the current and are independent of thermionic emission. Among the difficulties which may be mentioned, is the maintenance of the monatomic gas in a pure and uncontaminated condition. Slight traces of gaseous impurities, such as hydrogen, nitrogen, etc., liberated from the electrodes, the glass parts of the device or the insulators greatly increase the break 25 down voltage and the voltage drop through the device and if permitted to accumulate eventually cause the device to become inoperative at the normal voltage impressed across the terminals thereof.

30 It has been proposed heretofore to maintain the gas in a pure form by employing certain clean-up agents which react with the common gases to form solid compounds of low vapor pressure. Certain of these materials, however, contain considerable quantities of undesirable gas which is given off when the material is vaporized and is not subsequently eliminated by the getter material. For instance, magnesium, which is 35 most commonly employed as a gas clean-up, usually contains an appreciable quantity of hydrogen which is liberated when the getter is heated. Magnesium does not clean up hydrogen efficiently, however, and consequently, both the residual and liberated hydrogen are likely to remain in the tube as a gaseous impurity.

However, even though the monatomic gaseous filling is rendered extremely pure 40 during the manufacture of the device, never-

theless, with the electrode materials ordinarily employed, sufficient gases are given off by the electrodes and parts of the tube such as insulators, etc., during operation, probably due to bombardment by the discharge, to 55 contaminate the monatomic gas and greatly increase the resistance and voltage drop through the device.

It is one of the objects of the present invention to overcome the above mentioned 60 difficulties and to produce a gaseous conduction device in which the gaseous filling remains substantially pure and uncontaminated to an objectionable extent over a much longer period of operation and under more 65 severe conditions of operation than has heretofore been attainable.

Another object is to produce a device of the above mentioned character in which the electrodes will be composed of a material or 70 materials which facilitate the maintenance of the gas in a pure condition.

Another object is to provide a clean-up agent which is effective to remove substantially all traces of all of the common gases 75 and which in combination with the materials of which the electrodes are composed, will maintain the gaseous filling extremely pure.

A still further object is to provide and continuously maintain on the surface of one 80 of the electrodes a thin deposit of a material which will decrease the potential drop at the surface of the electrode.

Still another object is to provide a method of continuously maintaining such thin 85 deposit on the electrode throughout the life of the device.

Another object is to produce a gaseous conduction device which is capable of passing a discharge of relatively high voltage 90 and high amperage with a low and constant potential drop therethrough and in which the operating characteristics thereof will remain constant over a long period of operation.

95 Other objects and advantages will hereinafter appear.

We have discovered that when certain materials are employed for the cathode and anode of a gaseous conduction device to- 100

gether with an appropriate clean-up agent, the gaseous filling may be maintained in a substantially pure condition over a much longer period of time than has been possible heretofore under the same severe conditions of operation.

More specifically, we have found that when the cathode or plate electrode of a point to plate discharge device, such as a rectifier, is composed of one of the refractory metals such as molybdenum or tantalum and the active portion of the anode is composed of an active metal such as thorium, uranium or titanium and a clean-up or gas purifying agent, such as misch metal is employed, the gaseous filling does not become contaminated during operation of the device and the operating characteristics thereof remain substantially constant over many hundreds of hours of operation. Moreover, the voltage drop through the device is considerably lower after a few hours operation than when employing such metals as nickel, iron, etc., for the electrodes.

In order to further decrease the voltage drop through the tube, we may employ a deposit of an electro-positive metal, such as an alkaline earth or alkali metal on the cathode. In order to render such material effective throughout the life of the device, it is necessary to continuously replace the deposit during operation of the device. Simply coating the cathode itself with one of these materials is not sufficient, since the electro-positive metal is soon used up or vaporized away and is no longer effective. Tubes, the plates of which have been coated with such metals, while they show good characteristics on starting, do not maintain the same for a sufficiently long period of time to be of practical value.

The manner which we have found most effective for maintaining a deposit of an electro-positive metal on the cathode is by providing a quantity of a compound of an alkaline earth or alkali metal on the anode, which compound during operation is slowly reduced by the material of which the anode is composed to liberate the metal. This metal is then vaporized over on to the cathode and forms the desired deposit thereon. The thorium or uranium anodes may be dipped or otherwise coated with a solution of an alkaline earth compound such as barium or calcium nitrate or an alkali metal compound such as sodium or potassium nitrate. During the seasoning of the device, these nitrates are probably converted to an oxide and during the operation of the tube, these oxides are slowly reduced to metal. This metal is continuously vaporized on to the cathode, thus giving and maintaining a low starting and operating potential. We prefer to employ the alkaline earth metals, although the alkali metals are also satis-

factory. It is necessary, however, that the metal itself and not the oxide thereof, comprise the active deposit on the cathode. For instance, in certain experiments when barium oxide was applied directly to one side of the cathode it prevented the discharge from taking place with such coated surface and caused all the discharge to take place with the uncoated surface until after the oxide had broken down to metal. When employing molybdenum plates, any oxide which is carried over from the anode to the cathode is broken down by the reducing action of the metal which thereby assists in maintaining an active film of the electro-positive metal thereon. This is not true, however, with such metals as iron or nickel when employed as the plate material.

It is essential that a compound be employed on the anode which has a relatively low vapor pressure and which is not too active chemically, so that it will not be vaporized from the anode too rapidly. Such compounds as barium azide, for instance, do not serve effectively, because they completely vaporize away from the anodes very rapidly and are then no longer available to maintain the cathode deposit.

In place of dipping or otherwise coating the anodes, the alkaline earth or alkali compounds may be incorporated directly in the anode material during manufacture thereof, but in so doing, care must be taken to prevent the compound from being reduced and vaporized away during such manufacture.

The gas employed depends upon the output voltage desired. If a high voltage, that is, a voltage of from 200 to 300 volts is desired, the most suitable gas appears to be helium. With helium the inverse current is less than for either argon or neon under the same conditions and hence the tendency to arc is less. If lower voltages are desired, argon or neon are quite satisfactory and more efficient.

In order that the invention may be more fully understood, reference will be had to the accompanying drawings, in which:

Fig. 1 illustrates a gaseous conduction rectifier partly in section embodying the features of the present invention; and,

Figs. 2 and 3 illustrate circuit arrangements employed in seasoning the device.

The device comprises an envelope 1 containing a pair of anodes 2 and 3, a cathode 4 and a filling of a monatomic gas, such as helium, argon or neon or a mixture of such gases.

The anodes 2 and 3 are preferably composed of thorium, uranium or titanium and are carried by support wires 5 of nickel or other suitable metal secured to leading-in conductors 6 and 7 sealed through the press 8 of the device. The anodes may be se-

cured to the support wires 5 in any suitable manner, such as being threaded thereon, but in the embodiment shown, the nickel support wires pass into an opening in the anode, 5 and the anode is compressed about the support to frictionally engage the same. In order to restrict the discharge to the anodes, the support wires are enclosed in highly refractory insulating sleeves 9, preferably 10 composed of lavite or isolantite. A glass tube 10 fused to the press extends into a recess 11 in the lower end of the lavite sleeve and serves to support the same.

The cathode 4 is of cylindrical shape and 15 preferably is formed of a refractory metal, such as molybdenum, although any other convenient shape may be employed, giving the requisite surface area. The anodes 2 and 3 are illustrated as projecting into the 20 interior of the cylindrical cathode, but it is to be understood that, if desired, the anodes may be disposed externally of the cathode. By disposing the cathode about the anodes, it may be brought nearer to the press and the support wires made short 25 and direct, thereby producing a more rigid structure. The cathode is supported from the press by support wires 12 and 13 welded thereto, the former of which is joined 30 to a leading-in conductor 14 for supplying current thereto.

The leading-in conductors 6, 7 and 14 are connected to the terminal prongs 15, 16 and 17 respectively of the base 18.

35 A piece of misch metal or other metal of the cerium group of rare earth metals 19 is secured to the cathode by a strap 20 welded to the exterior of the cathode. The cathode is heated during exhaust by high frequency induction currents, to drive out the 40 gases therefrom and during such heat treatment, the misch metal is vaporized and deposits in a thin film on the bulb. This thin 45 deposit of misch metal assists in maintaining the gaseous filling pure throughout the life of the device.

The envelope is filled with monatomic gas, preferably helium, at a pressure from 5 to 20 mm. We prefer to employ about 12 50 mm. for an output voltage of from 200 to 300 volts and from 60 to 100 milliamperes. However, if lower output voltages are desired, argon or neon at a lower pressure may be employed.

55 The device after completion should be seasoned to develop the desired starting and operating characteristics.

The seasoning treatment which we have 60 successfully employed is conducted in two parts and is best understood by reference to Figures 2 and 3. The tube 20 is first operated for about 10 minutes directly across a 220 volt A. C. line 21 with the anodes 2 and 3 in series with 15 watt, 110 volt 65 tungsten filament lamps 22 and 23.

The seasoning is then continued with the anodes 2 and 3 joined together and connected to one side of a source 24 of direct current at from 400 to 500 volts, with the cathode 4 joined to the other side of the 70 line through a filter circuit 25 containing a load 26. The tube should be operated in this circuit until the anodes become heated to a bright red heat and there is no appreciable flashing between the anodes and 75 the cathode, at a voltage in excess of that which they will receive in use.

With a rectifier of the above construction, that is, employing thorium anodes, a molybdenum cathode, misch metal getter and a 80 filling of helium at about 12 mm. of mercury, an output voltage of around 200 volts at 85 milliamperes may be continuously maintained over many hundreds of hours. When employing plates of such metals as 85 iron or nickel and exactly the same transformer and filter circuit, an output of only about 150 to 160 volts or 85 milliamperes can be obtained after operating for about 100 hours or so. 90

In order to still further reduce the potential drop through the device, an alkaline earth or an alkali metal may be employed as a thin deposit on the cathode. In order to maintain this deposit throughout the life 95 of the device, it is essential to provide a reserve supply of such metal within the device and to continuously supply it to the surface of the cathode during the operation of the rectifier. Merely coating the cathode with such metal is not satisfactory, 100 since it rapidly vaporizes away and is no longer available. Therefore, in order to provide a reserve supply of such metal, we coat the anodes 2 and 3 with a compound 105 of an alkaline earth or alkali metal such as barium nitrate which is probably converted to oxide during seasoning, which slowly reacts with the thorium during the operation of the device to liberate the barium metal. 110 The barium is vaporized by the discharge and is continually supplied to the cathode. The reaction of the compound with the thorium is slow so that the compound is not entirely used up during the normal life of 115 the device.

The device of the present invention has been designed particularly as a rectifier for supplying plate current for radio receiving apparatus through the so-called B-eliminator apparatus. In such a use, the output 120 current is smoothed out by any appropriate filter circuit embodying inductance and capacities. In such circuits, the charge which builds up on the anode when the 125 same is negative is several times that on the cathode when the cathode is negative, due to the action of the condensers in the filter circuit. Thus, for instance, with an output voltage of around 200 volts, the charge on 130

the anode during the inverse cycle may amount to as high as 700 volts. Due to this high voltage on the anodes, the small inverse current which flows between the cathode and anode bombards the anode at a high velocity and materially assists in the reduction of the alkaline earth or alkali compound on the anode.

Obviously, other means may be employed 10 for maintaining the active deposit on the cathode, but we have found the method described above to be highly successful.

While we have shown and described but 15 a single embodiment of our invention, it is to be understood that many changes and modifications may be made therein without departing from the invention.

What is claimed is:

1. An electrode for a gaseous conduction 20 device composed of thorium and a nitrate of a metal of the class including the alkaline earth and the alkali metals.

2. An electrode for a gaseous conduction device composed of thorium having a coating 25 of barium nitrate thereon.

3. The method of producing and maintaining a deposit of an electro-positive metal on the cathode of a gaseous conduction device, comprising forming the anode of 30 thorium, coating said anode with a compound of the electro-positive metal decomposable by said anode and passing a discharge through the device to decompose the compound, liberate the electro-positive metal 35 and vaporize the same from the anode onto the cathode.

4. A gaseous conduction rectifier comprising an envelope containing a monatomic gas, a cathode operable below incandescence, 40 composed of molybdenum, an anode composed of thorium, a gas purifying agent including a metal of the cerium group of rare earth metals and a coating of a compound of an electropositive metal on the anode.

45 5. A gaseous conduction rectifier comprising an envelope containing helium gas at a pressure from 5 to 20 mm., a cathode composed of molybdenum, an anode composed of thorium, a gas purifying agent 50 composed of a metal of the cerium group of rare earth metals and a coating of barium nitrate on the anode.

In testimony whereof we have hereunto 55 subscribed our names this 19th day of July 1927.

HARVEY C. RENTSCHLER.
